INVENTOR —
KATE A. MOORSHEAD,
BY FRIGHT & COOK, P.P.S.

UNITED STATES PATENT OFFICE.

KATE A. MOORSHEAD, OF CHICAGO, ILLINOIS.

GARMENT-HANGER.

1,260,936.

Specification of Letters Patent. Patented Mar. 26, 1918.

Application filed September 13, 1917. Serial No. 191,115.

To all whom it may concern:

Be it known that I, KATE A. MOORSHEAD, a citizen of the United States of America, a resident of Chicago, in the county of Cook, 5 State of Illinois, have invented certain new and useful Improvements in Garment-Hangers, of which the following is a full, clear, and exact description, reference being had to the accompanying drawings, forming a part 10 of this specification.

My invention relates to garment hangers and the object of my invention is to produce a garment hanger of light and inexpensive material which will serve as a support for 15 ladies' waists and other garments and be readily packed flat among or between articles of clothing, so that when traveling there is no liability of wrinkling or injuring adjacent apparel.

20 My invention comprises a pair of wing members, supported by hanger straps secured thereto, the wing members having their inner adjacent ends flexibly joined and resiliently stiffened and the free ends 25 of the hanger straps being provided with button or clasp securing means whereby they may be joined together to form a loop for suspension purposes.

In the drawings—
30 Figure I is a plan view of my garment hanger as it appears when suspended to support a garment.

Fig. II is a longitudinal section through the hanger.

35 Fig. III is a bottom plan view of the hanger, partly broken out.

A designates the wing members which are preferably composed of stiff inner pieces 1 of cardboard or other sheet material, and 40 cloth outer pieces or sheaths 2. These sheaths 2 are joined along their adjacent inner edges for the production of the flexible hinge a.

45 Each wing member has attached to it the inner end of one of a pair of hanger straps B, the outer free ends of which are joined together by a button or clasp 5, forming a loop whereby the hanger may be readily applied to a rod, pole or other convenient support.

50 Adjacent the hinge a is provided a resili-

ent connection C which serves to hold the adjacent inner ends of the wing members from upward movement when the weight of a garment tends to pull the outer ends of the 55 wing members downward. The resilient connection C is preferably composed of strips 3 of metal, whalebone or other suitable material, the strips being inclosed by covering 4 secured to the under faces of the wing 60 members A.

It is evident that when the hanger is in service the straps B will so support the wing members that a garment placed thereover will be suspended in a very satisfactory manner in that the front and back of the garment will be spaced by the shape of the wing members in an airing position. When not in service the straps B may be unclasped and laid flat on the wing members A, whereby 70 the hanger becomes a flat object occupying a minimum of space and adapted to be placed between garments without wrinkling or injuring them.

75 It will be observed that metal parts, excepting the button or clasp and the perfectly flat reinforcing strips 3, are dispensed with. Heretofore, in producing hangers of this type, which contemplates horizontal wing members when in service, metallic 80 hinges, rods, etc., have been considered indispensable, and their presence has been attended with discomfort and injury to the adjacent garments when packed and unpacking.

85 I claim:

A garment hanger comprising flat wing members composed of stiff inner sheet material and sheaths therefor joined along their adjacent inner edges to form a flexible 90 hinge, hanger straps each having one end attached to a wing member and the other end provided with one member of a separable fastener, and a flat incased resilient stiffening connection bridging the flexible hinge 95 and held to adjacent parts of the wing members by being indirectly secured thereto through its casing.

In testimony that I claim the foregoing I hereunto affix my signature.

KATE A. MOORSHEAD.
